FINDING FOR A PIN JOINT

John R. Watson, Bristol, R. I.

Application February 8, 1954, Serial No. 28,913

Term of patent 14 years

(Cl. D45—19)

Fig. 1.

Fig. 2.

Fig. 3.

Fig. 4.

To all whom it may concern:

Be it known that I, John R. Watson, a citizen of the United States of America, residing at Bristol, county of Bristol, State of Rhode Island, have invented a new, original, and ornamental Design for a Finding for a Pin Joint, of which the following is a specification, reference being had to the accompanying drawing forming a part thereof.

Fig. 1 is a top view of a finding for a pin joint, showing my new design;

Fig. 2 is a side view thereof;

Fig. 3 is a bottom view thereof; and

Fig. 4 is an end view.

I claim:

The ornamental design for a finding for a pin joint, substantially as shown.
